US00D720451S

(12) **United States Design Patent**
Denenburg et al.

(10) **Patent No.:** US D720,451 S
(45) **Date of Patent:** ** Dec. 30, 2014

(54) **LIQUID DRUG TRANSFER ASSEMBLY**(75) Inventors: **Igor Denenburg**, Gedera (IL);
Mordechai Bukhman, Netanya (IL)(73) Assignee: **MEDIMOP Medical Projects Ltd.**,
Ra'anana (IL)(**) Term: **14 Years**(21) Appl. No.: **29/413,215**(22) Filed: **Feb. 13, 2012**(51) LOC (10) Cl. **24-02**

(52) U.S. Cl.

Primary Examiner — Deanna L Pratt*Assistant Examiner* — Ieisha Price(74) *Attorney, Agent, or Firm* — Panitch Schwarze Belisario
& Nadel LLP(57) **CLAIM**The ornamental design for a liquid drug transfer assembly, as
shown and described.

DESCRIPTION

FIG. 1 is a perspective view of a liquid drug transfer assembly
in accordance with a preferred embodiment of our new
design;

FIG. 2 is a left side elevation view thereof;

FIG. 3 is a front elevation view thereof;

FIG. 4 is a right side elevation view thereof;

FIG. 5 is a rear elevation view thereof;

FIG. 6 is a top plan view thereof; and,

FIG. 7 is a bottom plan view thereof.

1 Claim, 4 Drawing Sheets
